[57] CLAIM

The ornamental design for a vehicle body, as shown and described.

DESCRIPTION

FIG. 1 is a front view of a vehicle body showing my new design;

FIG. 2 is a rear view of the vehicle body of FIG. 1; and, FIG. 3 is an elevated side view of the vehicle body of FIG. 1, it being understood that the opposite side not shown is a substantial mirror image thereof.

It will be understood that the roof of the vehicle body is plain and unornamented.

It will be understood that the wheels shown in broken lines are for illustrative purposes only and form no part of the claimed design.
